UNITED STATES PATENT OFFICE.

CLARENCE C. STIRLING, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

SWITCH.

1,261,456.

specification of Letters Patent.

Patented Apr. 2, 1918.

Application filed June 22, 1917. Serial No. 176,301.

To all whom it may concern:

Be it known that I, CLARENCE C. STIRLING, a citizen of the United States, residing at Hartford, in the county of Hartford and State of Connecticut, have invented certain new and useful Improvements in Switches, of which the following is a specification.

This invention relates to switches, the object of the invention being to provide an appurtenance of this character which is simple in construction, susceptible of inexpensive manufacture and which can be rapidly moved to the on and the off positions.

In the drawings accompanying and forming part of the present specification I have shown one form of embodiment of the invention which will be fully set forth in the following description. I do not limit myself to this particular disclosure; I may depart therefrom in several respects within the scope of the invention defined by the claims following said description.

Referring to said drawings:

Figure 1 is a vertical sectional view of a switch involving the invention.

Fig. 2 is a transverse section of the same.

Fig. 3 is a horizontal sectional top plan view, the section being taken on the line 3—3 of Fig. 1, looking in the direction of the arrows.

Like characters refer to like parts throughout the several views.

The device involves in its make-up a body as 2 which may be made from any of the insulating substances now in customary use. This body is inclosed by the casing or housing 3 generally of sheet metal, the sections of which may be removably united by a suitable joint as familiar. There may be if desired interposed between the body 2 and casing or housing 3 an insulating lining 2' as usual in this type of article. In the upper section of the casing is a bushing as 4 of insulating material through which a suspending cord made of insulated wires 5, may extend. These wires within the casing 3 are bared and connected with screws 6, the heads of which are fitted in a channel 7 exterior of the insulating body 2, the shanks of the screws freely extending through perforations in said body and being in threaded connection with contacts as 8, the outer faces of which are conformed to the inner surface of the chamber 9 of the body 2, which chamber receives in addition to said two contacts

certain coöperating devices hereinafter described. The two contacts 8 as shown are disposed at opposite sides of the fin 10 which may be in one piece with the insulating body 2. When these contacts 8 are electrically bridged, it is clear that the circuit is closed.

The contactor or circuit controlling member is in the form of a roller 11 which virtually floats and which moves between the two contacts 8 which it bridges when the switch is closed. When the circuit is open the contactor engages the stop or buffer 12 on the wall of the chamber 9 practically diametrically opposite the fin 10.

The operating means for the contactor or roller involves an actuator as 13, the insulating body 2 and casing 3 having registering openings which receive the actuator 13 for sliding movement, the terminals of the actuator constituting buttons. As will be understood the contactor or circuit controlling member 11 consists of a metal roller through the central opening 14 of which the coiled spring 15 extends, the spring being virtually of inverted U-form. Its terminals are provided with eyes 16, which receive the transversely aligned screws 17 threaded into the bottom of the chamber or cavity 9. The transverse line which passes through these two screws is practically midway of the projections 10 and 12. This coiled spring is constantly under tension and holds the contactor 11 firmly against the two contacts. When the anti-friction roller 11 is in its on and off positions and also when between said positions as best illustrated in Fig. 1, it is slightly spaced or separated from the actuator 13. Said actuator 13 is shown as having a circumferential projection 16' directly coöperative with the roller 11 as will herein-after appear. This projection is made rigid with the actuator 13 in some suitable way; as shown it has united with it a flange 17', the lower part of the projection and the flange 17' being disposed in the counterbore 18 which extends below the chamber or cavity 9. The ends of the flange 17' when the switching member is on and off respectively engage the wall of the counterbore 18 and thus maintain the actuator 13 at all times in proper relation.

The roller 11 is shown as being in the off position by full lines in Fig. 1, resting against the stop 12. The full lines in this view also show the actuator 13 in the corre-

sponding position. It will be assumed that it is desired to close the circuit governed by the switch. In this event the following procedure may be adopted: The actuator 13 will 5 be thrust to the left in Fig. 1 to effect its movement from the full line to the dotted line position in said view. The projection 16' by riding against the periphery of the roller 11 will move under said roller and will 10 lift it and cause the roller to traverse the inner face of the stop 12, the motion continuing until the projection 16 passes from under the roller when the roller is at once moved to the on position by the power of 15 the spring 15. To open the circuit, the action described will be reversed. The act of moving the actuator also increases the tension of the spring just at the moment of 20 make or break, when quickness of movement is required.

What I claim is:

1. An electric switch comprising an anti-friction roller constituting a contactor, combined with a coiled spring extending through 25 the opening of the roller and tending constantly to move the same, and means for releasably holding the roller against movement.
2. An electric switch comprising a contactor having an opening, combined with spring means extending through the opening and tending constantly to move the contactor, and means for releasably holding the contactor against movement.
3. An anti-friction roller constituting a contactor combined with a coiled spring extending through the opening of the roller and tending constantly to move the same, and manually operable means for releasably 35 holding the roller against movement.
4. An electric switch comprising a contactor combined with a coiled spring approximately in U-form acting between its

ends against the contactor and tending constantly to move the same, and means for releasably holding the contactor against movement. 45

5. An anti-friction roller constituting a contactor combined with a coiled spring extending through the opening of the roller, the terminals of the spring being fixed and the spring tending constantly to move the roller, and manually operable means for releasably holding the roller against movement. 50

6. An electric switch comprising a contactor having an opening, combined with means extending through the opening and acting constantly to move the contactor, and means for releasably holding said contactor 55 against movement. 60

7. A contactor having an opening combined with a coiled spring extending through said opening, the ends of the spring being fixed and the spring tending constantly to 65 move the contactor, and a manually controlled actuator provided with a projection to engage the contactor to cause the same on opposite endwise movements of the actuator, to move between on and off positions. 70

8. An anti-friction roller constituting a contactor combined with a coiled spring extending freely through the opening of the roller to thus permit the latter to float, the ends of the spring being fixed and the spring 75 tending constantly to move the roller, and a reciprocating actuator provided with a projection to engage the roller to effect on and off movements thereof on opposite endwise movements of the actuator. 80

In testimony whereof I affix my signature in the presence of two witnesses.

CLARENCE C. STIRLING.
